UNITED STATES PATENT OFFICE.

JOSEPH G. BIXBY, OF LINCOLN, ILLINOIS.

SUPPORTING ELEMENT FOR FLAGS.

1,294,032.

Specification of Letters Patent. Patented Feb. 11, 1919.

Application filed May 7, 1917. Serial No. 166,798.

To all whom it may concern:

Be it known that I, JOSEPH G. BIXBY, a citizen of the United States, a resident of Lincoln, in the county of Logan and State 5 of Illinois, have invented new and useful Improvements in Supporting Elements for Flags, of which the following is a specification.

This invention has reference to means applied to flags for decorative purposes, whereby flags may be displayed in an attractive manner, unfurled and with the appearance of being whipped by the breeze, or straight out as in a stiff breeze, or with the flag having 15 the appearance of being blown upward as from an undercurrent of air, or, as is sometimes the case, partly wrapped around the flag staff.

The invention consists essentially of a supporting element, preferably of soft wire, serving as a binder for the selvage edges of the flag which is adapted to be bent into any desired shape, thus making it possible to make an entire change in a decorative 25 scheme with the same set of flags.

In the drawings;—

Figure 1 is a side view of a flag showing my flexible supporting element applied thereto;

Fig. 2 is a cross-section as the same would appear if taken on the line 2—2 of Fig. 1;

Fig. 3 is an edge view looking down on the flag;

Fig. 4 is a view of the supporting element, 35 and

Fig. 5 is a perspective of the manner of securing the supporting element to the selvage of the flag, and also to the staff.

Like characters of reference denote corresponding parts throughout the figures.

The flag is designated 1, attached in the usual manner to a flag staff 2.

3 designates a supporting element, preferably of soft wire, or equivalent material, 45 the same bent into the form shown, and having the spaced parallel portions 4 and 5 and the connected end portion 6. The ends of the element are preferably connected to the staff 2 by being coiled, as at 7, about the 50 same.

To connect the element 3 to the flag fabric,

the upper and lower selvage edges 8 and 9 of said flag are turned over the portions 4 and 5 of said element and pasted or otherwise suitably secured to its body, as shown 55 in Fig. 1. Turning over the selvage edges as shown, leaves the extended upper and lower parts 10 and 11 of the body of the flag to be secured about the staff 2, and I preferably coil the ends of the element about 60 these portions, as shown in Figs. 1 and 5.

I prefer to have the end portion 6 of said element merely cross the outer portion of the flag, near the edge, without overlapping said edge, leaving it free and making it possible 65 to have it fringed, if desired.

It is obvious from the foregoing that the portions 4 and 5 of the element 3 may be left straight holding the body of the flag from the staff and giving it the appearance, 70 as if in a stiff breeze; or the portions 4 and 5 of said element 3 may be bent somewhat as shown in Fig. 4 to show the flag in an attractive manner, unfurled, and with the appearance of being whipped by the breeze. 75

The use of flags for indoor decorations is universal, and the limp nature of flags made from cloth does not allow of the full beauty of flag decoration without much labor in draping, but with a supporting element of 80 the character described, the flags may be displayed in the most attractive manner with very little trouble.

What I claim is:—

1. A supporting element for a flag having 85 portions to stiffen the upper and lower selvage edges thereof and secured thereto, and also having a connecting end portion crossing the flag adjacent its free selvage.

2. A supporting element for a flag having 90 portions to stiffen the upper and lower selvage edges thereof, and also having a transverse connected portion crossing the body of the flag, the upper and lower selvage edges of said flag overlapping said element, a staff, 95 the ends of said element being connected to said staff.

3. In combination, a flag staff, a flag attached thereto, a supporting element for said flag comprising a piece of soft wire 100 bent into form to provide stiffening means for the upper and lower selvage edges of

said flag, and crossing the body thereof adjacent the front selvage edge, the ends of said wire connected to said staff, and the upper and lower selvage edges of said flag 5 overlapping the stiffening portions of said wire.

4. A supporting element for a flag, comprising a piece of soft wire having spaced parallel portions and an end piece, said spaced parallel portions bent to have a 10 wavy appearance.

JOSEPH G. BIXBY.
